COMBINATION IRONING TABLE AND
STEPLADDER

Pasquale Capriotti, Smithfield, Pa.

Application November 9, 1946, Serial No. 708,979

3 Claims. (Cl. 228—4)

1

My invention relates to new and useful improvements in combination devices and more particularly to a combined ironing table and stepladder, the primary object of the invention being to provide a simple, strong and efficient structure which may be readily and quickly set up as an ironing or other table and with little effort quickly converted into a stepladder.

A further object of the invention resides in the provision of means which, when the device is set up as a stepladder may be used as a support for various articles, but when the device is set up as an ironing board or table may in reverse also be used as a support for clothes prior or subsequent to the ironing thereof.

Still another object of the invention resides in the special means for supporting the platform or shelf and the means for actuation thereof to position same in operative and inoperative positions.

A further object of the invention resides in the provision of a special means for utilization of a back support for the stepladder which affords means for the support of the ironing board or other table.

A further object resides in the provision of a special means cooperating with the ladder support to act as a direct support for the ironing board when the ladder is set up in operative position.

Still another object of the invention resides in the provision of an ironing board which may be connected or disconnected with the device when in folded position.

A still further object resides in the provision of means for locking the rear support for the ladder in position when the device is set up for use as a ladder.

A still further object of the invention resides in providing a combination device of the class described which is simple and durable in construction, inexpensive to manufacture and one which will be very efficient and useful in operation.

With these and numerous other objects in view, my invention consists of the novel features of construction, combination and arrangement of parts, as will be hereinafter referred to and more particularly pointed out in the specification and claims.

In the accompanying drawings, forming a part of this application:

Figure 1 is a side elevation of the device, set up as an ironing table;

Figure 2 is a fragmentary side elevation of the device, illustrated in Figure 1 with the shelf or

2

platform lowered to folded or inoperative position;

Figure 3 is a vertical central longitudinal section through the device, as seen on the line 3—3 of Figure 4;

Figure 4 is a vertical transverse section through the device, as seen on the line 4—4 of Figure 3, looking in the direction of the arrows;

Figure 5 is a horizontal section through the device, as seen on the line 5—5 of Figure 3;

Figure 6 is a fragmentary horizontal section, as seen on the line 6—6 of Figure 3;

Figure 7 is a fragmentary transverse vertical section, taken on the line 7—7 of Figure 4;

Figure 8 is an enlarged fragmentary sectional view, as seen on the line 8—8 of Figure 4, showing particularly the manner in which the ironing board or table is hooked in position to the uprights and showing the relationship of the lower end of a slot in the uprights to the rear support of the latter;

Figure 9 is a detailed fragmentary perspective view of the ironing table removed and reversed to show particularly the hooks thereon.

Figure 10 is a perspective view of the shelf or platform removed, showing particularly the handle formed thereon and the structure of the inner end supporting portions thereof;

Figure 11 is a bottom perspective of a table element which may be substituted for the ironing table;

Figure 12 is a side elevation of the device set up as a stepladder, with the ironing board removed, and the shelf or platform positioned at the top of the ladder for use as a tool or article support;

Figure 13 is a front elevation of the device as illustrated in Figure 12;

Figure 14 is an enlarged fragmentary vertical section, as seen on the line 14—14 of Figure 13, looking in the direction of the arrows;

Figure 15 is a horizontal section, as seen on the line 15—15 of Figure 14;

Figure 16 is a similar view, as seen on the line 16—16 of Figure 14;

Figure 17 is a front elevation of the device entirely folded and out of use with the ironing board supported thereon;

Figure 18 is a side elevation of the device folded, as shown in Figure 17;

Figure 19 is a rear elevation thereof; and

Figure 20 is a horizontal section therethrough, as seen on the line 20—20 of Figure 19.

In rural districts and in apartments and small homes where conservation of space is essential, it is desirable to utilize kitchen and other devices

which are capable of dual functions and also capable of being disposed to inoperative positions without the utilization of any appreciable amount of space. Essentially, I have provided a device to be used as an ironing table or table for other uses in a kitchen or other small space, capable of being folded completely and disposed to an inconspicuous corner of the room, but which is also adapted, by reason of the structure for support and folding thereof, to be utilized as a stepladder. I am aware of the fact that combination ironing boards and stepladders have been known, but I have provided a simple device which is different in construction and operation from those heretofore known, capable of being more compactly folded and of greater usefulness, by reason of its simple manipulation than others now known.

In describing the invention, I refer to the drawings in which similar reference characters designate corresponding parts throughout the several views and in which the numeral 1 designates a pair of uprights which are held in spaced relation by means of the spaced apart cross bars 2, which together form a ladder. The cross bars 2 are supported in the front face of the uprights 1 and secured in position in any desired manner and the lower ends of the uprights 1 are bent or flared outwardly to a slight extent, as shown at 3. The inner opposed faces of the uprights 1 are each provided with a vertical slot 4 extending from a point near the top end of the upright to a point a little less than midway of said upright, and operating vertically in the slots 4 are the ends of a transverse rod 5. This rod is carried on the upper end of a rear support which comprises a pair of arms 6 held in spaced relation by a pair of transverse bars 7. The rear support with the pintle or bar 5 thereon is adapted to be moved with respect to the uprights and said rear support is held in connection with said uprights by means of the rods 8 which are hinged to said uprights at points designated by the numeral 9 at one end and pivotally connected as shown at 10 to angle irons 11 secured to a lower cross bar 2 connecting the uprights, as clearly shown in Figures 1 and 3 of the drawings. Thus, with permanent connection of the rear support to the ladder or uprights, it is possible by grasping the transverse rod 5 to lower the support to retain the uprights in substantially vertical position or to raise the rear support to dispose the same between the uprights in collapsed position therebetween. In order to substantially lock the rear support in its lowermost operative and effective position, the lower ends of the slots 4 in which the ends of the rod 5 operate are slightly curved rearwardly as shown at 12.

When the uprights 1 are supported in substantially vertical position by the disposition of the rear support to its lowermost and extended position, as shown in Figures 1 and 3, the device is in position for use in supporting a table top. In carrying out my invention, I provide an ironing board or table 13 which may be of any desired width and/or length, but which is of a width substantially equivalent to the outside measurements of the ladder. There is secured to the under face of the inner end of this board a block 14 which is of a width substantially equivalent to or slightly less than the inside measurement between, the bars 6 constituting the rear support, so as to fit therebetween and secured in any desired manner to said block adjacent the ends thereof are the hooks 15 which are adapted to en-

gage the bar 5 when the board or table is placed in position on the rear support.

In order to support the board or table 13 in a horizontal position, I have provided a table support comprising a pair of arms 16, the lower ends of which are hingedly connected, as shown at 17, to the lower cross bar of the rear support and the upper ends of said arms are secured together by means of a cross bar 18. The lower or under face of the table 13 has secured thereto at a predetermined point thereon a stop block 19, the front and rear edges of which are beveled, as shown at 20. Thus, when it is desired to utilize the table 13, it is hooked in position on the rod 5 and moved to a substantially horizontal position, whereupon the arms 16 are moved on their hinges upwardly so that the cross bar 18 thereof rides over the front beveled edge 20 of the block 19 to rest against the rear edge of the latter. The supported position of the table as it is described is best illustrated in Figures 1 and 3 of the drawings. When it is desired to remove or lower the table, it is only necessary to slightly lift the outer free end thereof and allow the cross bar 18 of the supporting arms 16 to be moved over the beveled edge of the block 19, whereupon the table supporting element will be returned to its collapsed position between the bars 6 of the rear support and the table allowed to drop to its position against the said rear support or removed entirely.

It will be seen, however, that when the table is dropped to its lowered position on the rear support, it need not be removed but may be carried to a collapsed position with the rear support on the uprights by the movement of said rear support upwardly through the operation of the bar 5 in the slots 4. In order to hold the table in locked position on the rear support in the movement of the latter with respect to said uprights, I provide a pivoted latch 21 on the block 14 which may be swung to a position so that the end thereof is in binding contact with the cross bar 5. This will prevent accidental displacement of the hooks 15 from the cross bar 5. Obviously, this latch member 21 may be effectively applied to lock the table in its operative position, that is in the position shown in Figures 1 and 3, if desired, although this is not necessary in order to operate the table, in view of its otherwise proper support.

I have described this table or board element 13 as an ironing board or table, since it is primarily used for that purpose. It has been found desirable, however, to utilize this device as a table or support for various other activities, such as the making of bread and other kitchen activities. As the ironing table would not serve so well for such a purpose, I have provided a substitute table which, as shown in Figure 11, is designated by the numeral 22. This table is preferably of greater width and possibly less length than the table 13 but is provided with the block 14 and the hooks 15 similar to the block and hooks previously described and used in connection with the table 13. It is also provided with a stop block 19 similar to the stop block 19 previously described, enabling the table to be properly supported in horizontal position.

As it is desirable to have some platform or support for clothes as same are ironed and as it is customary in certain types of stepladders to have supports thereon for tools and the like, I have provided a shelf or platform 23. This shelf or platform is supported on a pair of arms 24 which extend beyond the front and rear edges of said shelf. The front extending edges of said arms

24 are connected by an element 25 which may be referred to as a handle, being slightly spaced from the front edge of said shelf. The extending rear ends of said arms 24 are connected by a metal rod 26 and the upper edges of said arms at their rear ends are beveled, as shown at 27. The metal rod 26 is projected through slots 28 extending vertically in the upper end portions of the uprights 1 and the arrangement is such that the ends of the arms 24 slide against the outer faces of said uprights. In order to support the shelf in its substantially horizontal position for use when the device is set up as an ironing or other table, I provide a pair of laterally extending pins 29 in the uprights 1 in a plane just above the lower ends of the slots 28. Thus, when it is desired to position the shelf for use, it is moved upwardly with the rod 26 operating in the slots 28 then swung or tilted so that the inner ends of the arms 24 are in a plane forward of the pins 29 and then the rod 26 allowed to return to its lowermost position in the slots 28 and the shelf dropped to a horizontal position, whereupon the beveled upper edges of the rear ends of the arms 24 will contact with the pins 29 and retain the shelf in the horizontal position, as shown in Figures 1 and 3 of the drawings.

When it is desired to lower the shelf to a collapsed position, a reverse movement is taken, that is, the outer end of the shelf is tilted upwardly, then the shelf drawn upwardly, moving the rod 26 in the slots 28 to a position so that the ends of the arms 24 are above the horizontal plane of the pins 29, whereupon the outer end of the shelf is allowed to be dropped downwardly by gravity and then the entire shelf allowed to move downwardly with the rod 26 moving to its lowermost position in the slots 28. This collapsed position of the shelf or platform is illustrated in Figure 2 of the drawings.

When it is desired to use this device solely as a stepladder, the table 13, or the table 22, if used, is disconnected by lowering the table support 16 into the rear support of the ladder and unhooking the table from the rod 5. Then the rod 5 connecting the bars 6 of the ladder support is grasped and then with a forward motion to disconnect said rod from the curved end of the slot 4, the rod is drawn upwardly in the slots 4 to a point near the top of the uprights 1 where said rod is guided into forwardly and upwardly directed diagonal slots 30 communicating with said slots 4. By reason of the hinging connection of the bars 6 of the rear support with the uprights 1, this movement of the rod 5 upwardly in the slots 4 and into the diagonal slots 30 will tilt the uprights or ladder rearwardly, as shown in Figures 12 and 14.

When the device is set up for use as a stepladder, the shelf or platform may be found useful and may be brought into effective position. To accomplish this, the platform 23, from its collapsed position, as shown in Figure 2, for instance, may be moved upwardly in the slots 28 and by grasping the handle 25 the shelf may be given a turn over the upper ends of the uprights 1 until reversed and the shelf position on the side of said uprights from which the rear support projects. A supporting cross bar 31 secured to the rear edges of the uprights 1 has its ends 32 projected beyond the outer faces of said uprights and said ends aforesaid, form a rest for the side bars 24 of said platform. These supporting ends of the cross bar 31 together with contact of the rod 26 with the upper ends of the slots 28 will support

said platform in substantially a horizontal position on the ladder, as shown in Figures 12 and 14 of the drawings. It will be seen, however, that the platform when positioned in this manner for use in connection with the ladder is in reversed position and extended in the opposite direction from that in which same is positioned when used as a platform or shelf for the ironing table, the latter position being shown in Figure 1 of the drawings.

In order to lock the rear support in position when the device is set up as a ladder, I provide an additional cross bar 33 supported between the uprights 1 at the lower end of the slots 28 and suspended from said cross bar is a hook member 34 which, under spring tension may be engaged under the rod 5 when the ladder is positioned at the top of the diagonal slot 30, as clearly shown in Figure 14 of the drawings. When the hook is so engaged, it will be seen that the support for the ladder will be locked in position and securely brace the device in its ladder-operating position.

When the device is to be taken out of use entirely, the shelf or platform is first disposed over the front of the uprights to a position, as shown in Figures 2 and 19. Then, if the device is set up as a ladder, the hook member 34 is disengaged from the rod 5 and the rear support moved to a position so that the ends of the rod 5 are directed from the diagonal slots 30 into the vertical slots 4 and the support then raised until the ends of said rod 5 are moved to the upper ends of the slots 4. In this position, the side bars 6 of the rear support will be positioned substantially vertically between the uprights 1 and in frictional contact with the inner opposed faces of the ladder. The table or ironing board support will also be in a vertical position between the side bars 6 of the rear support and held frictionally therebetween. This folded position of the elements described is best illustrated in Figures 19 and 20 of the drawings. If it is desired to also support the ironing table 13 in this collapsed or folded position of the device, the hooks 15 of said table are engaged with the rod 5 just prior to the movement of said rod to its uppermost position in the slots 4 so that when the rear support is fully collapsed or folded within the uprights as shown in Figure 19, the table or board 13 will be suspended in place, as shown in Figures 17 and 18 of the drawings. In order to lock the table in that position against disengagement, the latch 21 is turned on its pivot to frictionally engage the rod 5, as is also clearly shown in Figure 19. In this position the device is a compact one which may be stored away quite readily in a small space.

An important element of this device, as heretofore described, is the shelf or platform which is so constructed and designed for movement between the uprights as to be utilized when the device is set up as a stepladder and when moved to a reverse position useful in cooperation with the device set up as an ironing table. As aforesaid, when the shelf is disposed to the position shown in Figures 12 and 14, it constitutes a tray or platform for tools or other articles that may be used when the operator is utilizing the device as a stepladder. The side arms or bars 24 of the shelf or platform in this position prevent articles from rolling off or casually dropping from the platform. When the platform is positioned for use in connection with the device when set up as an ironing table or the like, it will be seen that it may serve as a platform for supporting clothes that may have been properly ironed. Obviously,

a shelf or platform constructed in the manner shown and described and operable as heretofore set forth, is capable of various uses, according to the use to which the device as a whole may be put.

From the foregoing description of the construction of my improved combination collapsible ironing table and stepladder, the construction and operation thereof, and the method of applying same to use, will be readily understood, and it will be seen that I have provided a comparatively simple, inexpensive and efficient means for carrying out the various objects of the invention.

While I have particularly described the elements best adapted to perform the functions set forth, it is apparent that various changes in form, proportion and in the minor details of construction may be resorted to, without departing from the spirit or sacrificing any of the principles of the invention.

Having thus described my invention, what I claim is:

1. In a combination device of the class described, a pair of uprights, transverse bars connecting said uprights and retaining same in spaced relation, certain of said bars being adapted to form ladder-rungs, the inner opposed faces of said uprights having longitudinal grooves therein, a support for said uprights, a brace having one end pivotally connected with the intermediate portion of said support and its other end pivotally connected with one of the lower bars of said uprights, a transverse rod carried at the upper and inner end of said support having its ends slidably and hingedly operating in the grooves of said uprights, the lowermost ends of said grooves being curved to form locking ends for said transverse rod, there being diagonally extending grooves extending at an upward incline from upper portions of the longitudinally extending grooves for receiving ends of the transverse rod to hold the support in position to retain the uprights in ladder-forming position, a table having hooks at its inner end detachably engageable with the transverse rod, and a prop pivoted at one end to the lower portion of the support for swinging movement to a raised position in which its upper end bears against the under face of the table and supports the table in a horizontal position.

2. In a combination device of the class described, a pair of uprights, transverse bars connecting said uprights and retaining the same in spaced relation, certain of said bars forming ladder-rungs, the inner opposed side faces of said uprights being provided with longitudinal grooves and the lower ends of said grooves being curved, said inner opposed side faces of the uprights being each also provided with a diagonal groove communicating with the aforementioned groove and located at a point adjacent the upper end of said upright, a support for the uprights, means hingedly connecting an intermediate portion of the support with a lower cross bar of the uprights, a transverse rod carried at the upper and inner end of said support having its outer ends

slidably and pivotally engaged in the grooves of said uprights, the curved lower ends of said grooves forming a lock for the rod when moved to the lowermost position of the grooves, a table top adapted for detachable connection with said rod, and hinged means on said support forming an auxiliary support for said table top, the diagonal grooves in said uprights being adapted to receive the ends of said transverse rod when the rod is moved in the grooves upwardly to a position to support the uprights as a ladder.

3. In a combination device of the class described, a pair of uprights, transverse bars connecting said uprights and retaining the same in spaced relation, certain of said bars forming ladder-rungs, the inner opposed side faces of said uprights being provided with longitudinal grooves and the lower ends of said grooves being curved, said inner opposed side faces of the uprights being each also formed with a diagonal groove having its lower end communicating with the aforementioned groove and located at a point spaced downwardly from the upper end of said upright, a support for the uprights, means hingedly connecting an intermediate portion of the support with a lower cross bar of the uprights, a transverse rod carried at the upper and inner end of said support having its ends projecting laterally from the support and slidably and pivotally engaged in the longitudinally extending grooves of said uprights, the curved lower ends of said grooves forming a lock for the rod when the rod is moved to the lower ends of the grooves, the ends of the rod being engageable in the diagonally extending grooves when the support is shifted upwardly into position to support the uprights as a ladder, a table top having hooks at its inner end for detachable connection with said rod, an abutment strip extending across the under face of said table, and a prop pivoted at one end to said support and movable upwardly to a position disposing its upper end against the under face of the table and against the abutment strip to support the table in a horizontal position.
